United States Patent Office

Des. 199,719
Patented Dec. 1, 1964

199,719

PURSE MIRROR

David B. Smith, Columbus, Ohio, assignor to Acme Specialty Manufacturing Co., Toledo, Ohio, a corporation of Ohio

Filed Mar. 25, 1963, Ser. No. 74,118

Term of patent 3½ years

(CL D86—10)

Fig. 1

Fig. 2

Fig. 3

FIG. 1 is a front elevational view of a purse mirror showing my new design;

FIG. 2 is a side elevational view thereof; and

FIG. 3 is a bottom plan view thereof.

I claim:

The ornamental design for a purse mirror, as shown.
